UNITED STATES PATENT OFFICE.

WILLIAM H. GRIMSDALE, OF TWICKENHAM, ENGLAND, ASSIGNOR TO GRIMSDALE'S PATENTS LIMITED, OF LONDON, ENGLAND.

PIANO-PLAYER AND LIKE INSTRUMENT.

1,036,830.

Specification of Letters Patent. Patented Aug. 27, 1912.

Application filed August 26, 1910. Serial No. 575,127.

To all whom it may concern:

Be it known that I, WILLIAM HENRY GRIMSDALE, a subject of the King of Great Britain and Ireland, residing at "Brantwood," Stratford Road, Twickenham, in the county of Middlesex, England, have invented certain new and useful Improvements in and Relating to Piano-Players and Like Instruments, of which the following is 10 a specification.

This invention relates to mechanical piano players and like instruments, and has for its object to construct the piano player in an improved manner, so that with a given 15 vacuum in the vacuum chamber, the strength with which the several keys of the piano or the like are struck corresponds with the areas respectively of the air passages through the music sheet into the tracker board apertures through which the keys are actuated.

In the following description the word "relay" is used to indicate a chamber or passage in communication with pneumatics 25 adapted to operate valves between the striking pneumatic and the main vacuum chamber. The words "relay motor" or "motor of the relay" are used to indicate the pneumatics which actuate the valves between the 30 striking pneumatics and the main vacuum chamber.

In mechanical piano players and like instruments operated by the admission of air to relays through apertures of varying 35 area, the air pressure in the relay is determined by the opposing actions of air being admitted through the tracker board and air being drawn out through the small exhaust aperture which is continually open.

40 The pressure in the relay and the thrust on a sticker operated by a motor on the relay therefore varies with the area of the air passage through the music sheet into an aperture in the tracker board.

45 With a narrow perforation over a tracker-board aperture the pressure in the corresponding relay will be small, and with a broader perforation the pressure will be greater. A number of apertures of different area may be provided between the 50 vacuum chamber and the striking pneumatic and said apertures may be controlled by an equal number of valves requiring different thrusts to operate them, the valves requiring

small thrusts controlling the small apertures 55 and the valves requiring larger thrusts controlling the larger aperture. In such an instrument with a smaller pressure in the relay, the valve requiring the smallest thrust will be first operated, opening a small aperture between the vacuum chamber and the striking pneumatic, and if the differing thrusts required to operate the valves are due to the differing areas of the valves acted upon by the pressure of the air in the valve 60 chamber, the valves will open one after the other in the order of their increase of area, as the pressure in the valve chamber and striking pneumatic decreases. It will be seen that with a small pressure in the relay 65 there will be longer intervals between the opening of successive valves than with a larger pressure in the relay, and that it is possible to so proportion the area of the valves that with a small pressure in the relay only the smallest valve will be operated 70 in the time taken to strike a note and a soft note will result, and with a large pressure in the relay that the intervals between the openings of the successive valves are so 75 small that all the valves will be operated at such short intervals, and the striking pneumatic exhausted so quickly that a loud note will result.

The invention consists in providing two 85 or more valves controlling separate passages between the striking pneumatic or pneumatics corresponding to each key and the vacuum chamber, and a relay having one or more motors for operating said valves, the 90 valves and motors being so arranged that the intervals between the opening of the successive valves is shorter or longer, causing the striking pneumatic to strike a key with greater or less force according as a larger 95 or smaller air passage is opened through the music sheet into the corresponding aperture in the tracker board.

The invention further consists in providing 100 for each key a striking pneumatic controlled by a relay to which air is admitted through the tracker board the relay operating a compound valve consisting of a sticker on which are threaded a number of valves or disks, requiring different thrusts to operate them said valves having apertures of 105 different areas, the valves being operated consecutively in the travel of the motor of

the relay by means of shoulders on the sticker.

The invention also consists in providing in connection with each striking pneumatic 5 a relay provided with a number of separate motors connected to a single aperture in the tracker board, each motor controlling a valve.

The invention further consists in the improved 10 construction of mechanical piano player hereinafter described.

Referring to the accompanying drawings, Figure 1 is a section showing one form of the invention. Fig. 1^a is a section showing 15 the arrangement of the tracker board and pneumatics. Figs. 1^b and 1^c are detail views of one of the valves shown in Fig. 1. Fig. 2 a section of a modified form showing a 20 method of closing the communication between the striking pneumatics and atmosphere which is also applicable to other piano players. Fig. 3 is a section of another modification of the invention.

In carrying the invention into effect according to the form shown in Fig. 1 the piano player is provided with a striking pneumatic *a*, for each key of the piano which is in communication with a valve chamber *b*, in which there is situated a compound 25 valve controlling a passage *c* leading to the vacuum chamber *d*. The compound valve comprises a number of separate co-axial circular valves or disks *e* of different diameters threaded on a sticker *f* carrying a valve, *m*, 30 the sticker being actuated by a relay motor *g* to which air is admitted through the music sheet and tracker board. The first valve *m* is fixed to the sticker *f* and so arranged that on the first movement of the sticker a small 35 aperture is opened between the valve chamber *b* and the vacuum chamber *d*. The sticker is provided with a number of shoulders *h* so arranged that on the further movement of the sticker the second of the disks or 40 valves is lifted away from the third by the first shoulder on the sticker, and an aperture of larger area is thus opened from the valve chamber to the vacuum chamber. On a further movement of the sticker the second 45 shoulder lifts the third valve or disk and opens a further passage by which air can pass from the valve chamber to the vacuum chamber. In a similar manner any desired number of valves or disks may be 50 provided, so that during the movement of the sticker, the total area of the passage leading from the valve chamber to the vacuum chamber is increased in steps.

The valves or disks *e* in the form above described are provided with apertures in Figs. 1^b and 1^c through them leading to circular grooves *j*, the total cross section of the apertures increasing from the valve first opened down to that last opened on the movement 65 of the relay motor. By constructing the

valves in this manner the area of opening may be accurately adjusted by regulating the area of the holes through the valves.

Any suitable form of valve such as *h*, closing automatically when the striking pneumatic is in communication with vacuum may be provided, to shut off the normal connection of the striking pneumatic to atmosphere; or, if desired, a separate motor may be provided for actuating a valve adapted 70 to open and close the communication of the valve chamber and striking pneumatic to atmosphere. This may be done as shown in Fig. 3 or it may conveniently be effected as shown in Fig. 2, where the smallest valve *q* 75 is operated by a separate relay motor *r* on the top of a main relay motor *s* which operates the larger valves by means of the sticker *f* as above described. I find that by using in this way a separate motor and valve 80 arranged to close the atmospheric inlet before the striking pneumatic is opened effectively to the vacuum chamber the rapidity 85 of operation is much increased. It will also be seen that as the connection between the 90 striking pneumatic and atmosphere is closed before the valves between the striking pneumatic and the vacuum chamber are operated the only air admitted to the vacuum chamber during the operation of the striking 95 pneumatic is the air in the striking pneumatic and valve chamber and therefore the power required to operate the main bellows of the piano player is less than in the case of piano players in which the valves operating 100 the striking pneumatic let external air into the piano player in this passage from one seat to another.

According to another modification of the invention shown in Fig. 3, the valve chamber *f* in connection with each striking pneumatic *a* is provided with two or more passages *c* leading to the vacuum chamber, these passages being of different areas, and each being controlled by a valve *e* actuated 110 by a separate relay motor *g* to which air is admitted through a single passage in the tracker board. In this modification also the smallest valve is made to close the passage between the striking pneumatic and atmosphere, the sticker making a sliding fit with the partition through which it passes between the valve chamber and vacuum chamber but an aperture may be formed as shown in the illustration in which case the valve 115 will be used to control the smallest aperture as well as the passage between striking pneumatic and atmosphere.

In piano players of the type above described in which the strength of stroke of 125 the striking pneumatic depends on the area of the air passage through the music sheet into the tracker board *r* I find that in order to enable me to use perforations in the music sheet giving a uniform increase of 130

area for uniform increase of intensity of stroke it is advisable to modify the apertures in the tracker board, and to form these so that there is a sudden increase in the 5 area of the apertures from the mouth of the opening inward, and I find that in this manner I am enabled to obtain an apparatus in which the pressure in the relays is proportional to the area of the air passages 10 through the music sheet into the tracker board.

Having thus described my invention, what I claim as new and desire to secure by Letters Patent is:—

15 1. In a mechanical piano player, means for varying the strength of blow by varying the time at which a plurality of valves between each striking pneumatic and the vacuum or pressure chamber are consecutively operated; said means including, a 20 tracker-board having a single aperture for each key, a single chamber always maintained during playing at a pressure different from atmospheric pressure, a plurality of 25 striking pneumatics one for each key, a plurality of passages directly between each striking pneumatic and said chamber, a plurality of valves one controlling each of said 30 passages, valve operating motor means in communication with each of said apertures adapted to operate said valves consecutively at each actuation of the corresponding key and means for varying the air admission area into each of said apertures in said 35 tracker-board.

2. In a mechanical piano player, means for varying the strength of blow by varying the time at which a plurality of valves between each striking pneumatic and the 40 vacuum or pressure chamber are consecutively operated; said means including a tracker-board having a single aperture for each key, a single chamber always maintained during playing at a pressure different 45 from atmospheric pressure, a plurality of striking pneumatics one for each key, a plurality of passages of different cross section directly between each striking pneumatic and said chamber, a plurality of

valves controlled only by air pressure one 50 controlling each of said passages, valve operating motor means of equal power in communication with each of said apertures adapted to operate said valves consecutively at each actuation of the corresponding key 55 and means for varying the air admission area into each of said apertures in the tracker-board.

3. In a mechanical piano player striking pneumatic means, an exhaust chamber, a 60 plurality of passages between each of said striking pneumatic means and said exhaust chamber, a valve controlling each of said passages, a valve-engaging device having shoulders adapted to engage said valves 65 consecutively upon movement of said device, a tracker-bar and motor relay means in communication with said tracker-bar actuating said valve-engaging device to open said valves consecutively at varying 70 intervals of time according as the air pressure is varied in the said motor relay means.

4. In a mechanical piano player, striking pneumatic means, a chamber, a plurality of 75 passages between said striking pneumatic means and said chamber, valves controlling said passages, a valve-engaging device having shoulders adapted to engage said valves consecutively, a tracker-bar and a motor relay in communication with said tracker-bar 80 actuating said valve-engaging device to open said valves consecutively.

5. In a mechanical piano player the combination of striking pneumatic means, a 85 chamber, a compound valve disposed between said chamber and said striking pneumatic means, said compound valve comprising a valve stem passing through a number of valves or disks having apertures of different area, relay motor means for operating said valve stem said relay motor means 90 acting to operate said valves consecutively.

In testimony whereof, I affix my signature in presence of two witnesses.
